UNITED STATES PATENT OFFICE

150,667

DESIGN FOR AN ORGAN TONE CABINET GRILLE

Victor I. Zuck, Kenmore, N. Y., assignor to The Rudolph Wurlitzer Company, North Tonawanda, N. Y., a corporation of Ohio

Application April 1, 1947, Serial No. 138,089

Term of patent 7 years

(Cl. D56—4)

To all whom it may concern:

Be it known that I, Victor I. Zuck, a citizen of the United States, residing at Kenmore, Erie County, New York, have invented a new, original, and ornamental Design for an Organ Tone Cabinet Grille, of which the following is a specification, reference being had to the accompanying drawing, forming a part thereof.

Fig. 1 is a front view of an organ tone cabinet grille showing my new design; and

Fig. 2 is a side view thereof.

The dotted line showings in the drawing figures are for illustrative purposes only.

I claim:

The ornamental design for an organ tone cabinet grille substantially as shown and described.

VICTOR I. ZUCK.
